No. 757,211.

PATENTED APR. 12, 1904.

W. I. MANN.

ELEVATING AND LOWERING DEVICE FOR BLAST FURNACE BELLS.

APPLICATION FILED DEC. 23, 1902.

NO MODEL.

UNITED STATES PATENT OFFICE.

WILLIAM I. MANN, OF PITTSBURG, PENNSYLVANIA.

ELEVATING AND LOWERING DEVICE FOR BLAST-FURNACE BELLS.

SPECIFICATION forming part of Letters Patent No. 757,211, dated April 12, 1904.

Application filed December 22, 1902. Serial No. 136,269. (No model.)

To all whom it may concern:

Be it known that I, WILLIAM I. MANN, a citizen of the United States, residing at Pittsburgh, in the county of Allegheny and State of Pennsylvania, have invented new and useful Improvements in Elevating and Lowering Devices for Blast-Furnace Bells, of which the following is a specification.

This invention relates to certain new and useful improvements in elevating and lowering devices, and is particularly adapted for use in connection with blast-furnaces, and is also adapted for elevating and lowering objects of any character for which it is applicable.

15 The invention aims to provide a new and improved elevating and lowering device for use in connection with handling blast-furnace bells which is adapted for holding the bell in its normal or closed position for lowering the bell 20 as occasion requires and for automatically returning the bell to its normal or closed position, at the same time cushioning the return movement of the bell.

25 The invention further aims to provide an elevating and lowering device particularly adapted for the bells of blast-furnaces which shall be extremely simple in its construction, strong, durable, efficient in its operation, and comparatively inexpensive to set up.

30 To this end the invention consists of the novel combination and arrangement of parts hereinafter more specifically described, illustrated in the accompanying drawings, and particularly pointed out in the claims hereunto appended.

35 In describing the invention in detail reference is had to the accompanying drawings, forming a part of this specification, wherein like reference characters denote corresponding parts throughout both views, and in which—

40 Figure 1 is a sectional side elevation of my improved device as connected to the bell of a blast-furnace, and Fig. 2 is a detail plan view 45 of my improved device.

I have shown my improved elevating and lowering device as used in connection with the bell of a blast-furnace, and, referring to the drawings by reference characters, 1 denotes the blast-furnace, and 2 the bell thereof.

Connected to the apex of the bell, as at 3, is the upper end of a flexible elevating and lowering member 4—such, for example, as a cable—and which passes over a sheave 5, supported in any suitable manner above the top 55 of the furnace.

The reference character 6 denotes a piston provided with a piston-rod 6^a and which is mounted in an air or hydraulic cylinder 7. As shown, an air-cylinder is employed and is 60 adapted to form a cushion for the purpose hereinafter referred to. The cylinder 7 at its top is provided with air-outlets 6^b, at its bottom with an air-inlet valve 6^c, and in the side thereof near its bottom with a petcock 6^d, 65 forming an outlet, this latter outlet being smaller than the inlet formed by the check-valve 6^e. The piston 6 is also provided with a piston-rod 8, which extends through the bottom of the cylinder 7 and is suitably connected at its lower end to the counterweight 9. As shown, the cylinder 7 and counterweight 9 are mounted in a suitable opening 70 formed in the ground or below the ground-level; but it is obvious that the cylinder 7 and counterweight 9 can be arranged above the ground and mounted upon a suitable support. The upper end of the piston-rod 6^a is connected to the lower end of the flexible member 4, as at 6^f.

75 The reference character 10 denotes a rocking drum carrying a flexible connecting member 10^a, which is connected at one end to the drum, as at 10^b, and at its lower end to the piston-rod 6^a, as at 10^c. The rocking drum 80 10 is loosely mounted upon a shaft 12 and is provided with a clutching-sleeve 13, adapted to engage the clutching-collar 14 of the drive-pulley 15, fixed on a driven shaft 12. The pulley 15 is connected by a belt 16 or a gear 85 90 ing to a prime mover. (Not shown.) The clutching-collar 14 is adapted to be engaged by a shifting-rod 14^a for bringing the said collar into engagement with the clutch-sleeve 13, so as to fix the drum 10 upon the shaft 12 95 and cause the drum to rock for a purpose hereinafter described. The clutching-sleeve 13 carries a suitable brake 17, so that the rocking motion can be retarded or the drum rocked independently of the prime mover.

The operation of the device is as follows: Movement is imparted to the drum 10 in the direction as indicated by the arrow 18 by the prime mover. The counterweight 9 and piston 8 will be elevated owing to the winding of the flexible connection 10^a upon the drum 10. Such movement will also elevate the flexible member 4 and lower the bell 2 by gravity, owing to the weight of the bell or owing to the combined weight of the bell and the charge of ore or material upon the bell. The bell 2 is automatically returned to its normal or closed position by means of releasing the clutching-sleeve and collar from one another, which will disconnect the drum 10 from the shaft 12 and permit the counterweight 9 to lower. By releasing the brake 17 the piston 6 will lower as well as the counterweight 9—that is to say, when the drum has been operated in one direction by the brake 17. The lowering of the movement of the piston 6 and counterweight 9 can also be retarded by the brake 17. It will be evident also that the movement of the counterweight will be retarded owing to the action of the piston 6 and the cylinder 7, the cylinder 7 forming an air-cushion which retards the movement of the counterweight, so that the return of the bell to its closing position will be in a slow or gradual manner. The cylinder 7, as before stated, will be open to the atmosphere if air is used. By the example shown the top of the cylinder 7 is provided with a perforated cover, or other suitable construction may be employed, if desired. The bottom of the cylinder below the piston, as before stated, is provided with a check-valve, so that air may be drawn in the cylinder on the upstroke of the piston, but cannot escape through the check-valve on the downstroke of the piston. A small petcock, as before stated, is connected to the cylinder near the bottom in the side, so as to regulate the outflow of the air, so that the piston will slowly settle down and allow the bell to seat, or, in other words, the lowering movement of the flexible member will be in a cushioned manner. It is obvious that the piston will not retard the motion of the counterweight until the air has been compressed to a large extent within the cylinder. It is obvious that when using the brake to lower instead of the rocking drum if the clutch should be thrown out without application of the brake the counterweight would drop suddenly until near the end of the stroke, when it would stop and dance on the cushioned air. This would cause trouble or inconvenience. So, therefore, it is intended to control the speed of the drum by means of the brake. The air-cushion formed by the cylinder 7 and piston 6 forms an additional safety device to reduce shock of seating the bell, whether lowered by the brake or by the prime mover, and would very likely save a breakdown in case of failure of brake or drum connections, and

preferably the brake is employed when returning the bell to its normal position or the reseating of the bell. The brake can be operated in any suitable manner.

It is thought that the many advantages of an elevating and lowering device constructed in accordance with the foregoing description, taken in connection with the accompanying drawings, can be readily understood, particularly the overcoming of the objection of lowering the bells by hand as well as by levers connected to and operated by air or steam cylinders, and it will furthermore be evident that changes, variations, and modifications can be resorted to without departing from the spirit of the invention, and I therefore do not wish to restrict myself to the details of construction as hereinbefore set forth, but reserve the right to make such changes, variations, and modifications as come properly within the scope of the protection prayed.

Having thus fully described my invention, what I claim as new, and desire to secure by Letters Patent, is—

1. A device for elevating and lowering blast-furnace bells comprising a flexible member adapted to be connected directly to the bell, a rocking drum, an air-cylinder, a piston operating in said cylinder and connected directly to said flexible member, a counterweight connected to the said piston, a flexible connection between said piston and said drum, and operating means for said drum.

2. A device for elevating and lowering blast-furnace bells comprising a flexible member adapted to be connected directly to the bell, a rocking drum, an air-cylinder, a piston operating in said cylinder and connected directly to said flexible member, a counterweight connected to the said piston, a flexible connection between said piston and said drum, operating means for said drum, and means for retarding the movement of said drum.

3. A device for elevating and lowering blast-furnace bells comprising a cable connected at its upper end to the bell, a rocking drum, an air-cylinder, a piston operating in said cylinder, a piston-rod connected to said piston and extending above and below the same, said upper end of said piston-rod connected to the lower end of said cable, a flexible connection between the upper end of said piston-rod and said drum, a counterweight connected to the lower end of said piston, and means for operating said drum.

4. A device for elevating and lowering blast-furnace bells comprising a cable connected at its upper end to the bell, a rocking drum, an air-cylinder, a piston operating in said cylinder, a piston-rod connected to said piston and extending above and below the same, said upper end of said piston-rod connected to the lower end of said cable, a flexible connection between the upper end of said piston-rod and said drum, a counterweight connected to the lower end of said cable, and means for operating said drum.

lower end of said piston, means for operating said drum, and means for retarding the movement of said drum.

5. A device for elevating and lowering blast-furnace bells comprising a flexible member connected directly at its upper end to the bell, a gravity-retumed cushioning device for the bell connected directly at its upper end to the lower end of said flexible member, a rocking drum, and a direct flexible connection between said drum and the upper end of the cushioning device, said drum when operated adapted to elevate said flexible connection causing thereby the lowering of the bell and said cushioning device adapted through intervention of said flexible member to return the bell by gravity to its closing position.

10 6. A device for elevating and lowering blast-furnace bells comprising a flexible member connected directly at its upper end to the bell,

a gravity-retumed cushioning device for the bell connected directly at its upper end to the lower end of said flexible member, a rocking drum, a direct flexible connection between said drum and the upper end of the cushioning device, said drum when operated adapted to elevate said flexible connection causing thereby the lowering of the bell and said cushioning device adapted through intervention of said flexible member to return the bell by gravity to its closing position, and means for retarding the movement of said rocking drum.

15 In testimony whereof I have hereunto set my hand in presence of two subscribing witnesses.

WILLIAM I. MANN.
